UNITED STATES PATENT OFFICE.

MAX BLIEDEN AND JOHN HUBERT DAVIES, OF LONDON, ENGLAND.

INTERNAL-COMBUSTION ENGINE.

No. 891,901.

Specification of Letters Patent.

Patented June 30, 1908.

Application filed August 4, 1905. Serial No. 272,786.

To all whom it may concern:

Be it known that we, MAX BLIEDEN, American citizen, of Rosettenville, Johannesburg, Transvaal Colony, South Africa, and 5 586 Salisbury House, London Wall, London, England, and JOHN HUBERT DAVIES, British subject, of 586 Salisbury House, London Wall, London, England, have invented a new and useful Improved Internal-Combustion 10 Engine, of which the following is a specification.

This invention relates to internal combustion turbines, and consists in an improvement whereby the effective range of the temperature changes of the working fluid is increased, which renders it practicable to efficiently extract the available mechanical energy of the working fluid by a comparatively small number of vane rings rotating 20 with moderate peripheral speeds.

The series of operations which the working fluid is made to pass through, in succession, according to our invention may be briefly stated to be as follows:—A. Raising the 25 pressure of the atmospheric air and the fuel from the pressure of the atmosphere to the pressure of the combustion chamber. B. Combustion of the fuel preferably at constant pressure. C. Reduction of the working 30 fluid (*i. e.* the products of combustion diluted with the excess of atmospheric air) in suitably formed nozzles to a pressure below that of the atmosphere, the pressure energy of the working fluid being converted 35 into kinetic energy. D. Abstraction of a certain portion of the kinetic energy of the working fluid by the rotating vane-rings of the turbine. E. Preferably cooling the working fluid and thereby increasing its density 40 by the injection of water. F. Conversion of the remaining kinetic energy of the working fluid into pressure energy as the working fluid is discharged through suitably shaped nozzles or passages into the atmosphere.

Several forms of internal combustion turbines are at present known. In some of them the combustion of the fuel takes place at a constant pressure to which the atmospheric air and the fuel have been raised previous to the combustion. In others the combustion of the fuel takes place explosively (*i. e.* approximately at constant volume) the pressure of the working fluid rising 55 during the combustion. We consider that the mode of combustion at approximately

constant pressure is more suitable in connection with a turbine than the explosive mode of combustion, and we therefore preferably adopt the former, though our invention is 60 also applicable to the other mode of combustion.

An essential and now well-understood feature of all internal combustion turbines is a considerable reduction of the pressure of the 65 working fluid through adiabatic expansion in suitably shaped nozzles whereby its temperature is reduced and its pressure energy is converted into kinetic energy before the working fluid is allowed to impinge upon the 70 revolving vanes of the turbine.

Let t_1 be the temperature of the working fluid on the completion of the combustion, and p_1 the pressure in the combustion chamber, and let t_2 and p_2 be the temperature and 75 pressure respectively of the working fluid at the point where it first comes in contact with the turbine vanes; then the following equation holds good:—

$$\frac{t_1}{t_2} = \left(\frac{p_1}{p_2}\right)^n$$

80

the value of n being approximately 0.26 or 0.27 for adiabatic expansion, allowance being made for moderate friction.

It is obvious that t_2 must not exceed the temperature which the turbine vanes can stand without injury. Friction of the working fluid in the turbine will tend to raise its 90 temperature above the value of t_2 hence either t_2 will have to be less than the temperature which the turbine vanes can stand, so as to make allowance for the subsequent rise of temperature in consequence of friction, or else the working fluid must be allowed to expand below p_2 in the turbine so that the cooling effect of this expansion neutralizes the heating effect of friction. Which- 95 ever method be adopted, it is obvious that, 100

with a given ratio $\frac{p_1}{p_2}$ the temperature t_1 which the working fluid may be permitted to attain in the combustion chamber will be limited by the temperature which the turbine vanes can stand, and consequently unless the ratio $\frac{p_1}{p_2}$ be made very large, the thermodynamic advantages of the process of internal combustion, which depend principally 110 upon the magnitude of t_1 , will be lost.

There are several objections to the use of a

high pressure p_1 in the combustion chamber, particularly if the compression is to be effected by a compressor of the turbine type.

5 In our improvement we raise the ratio $\frac{p_1}{p_2}$ in internal combustion turbines, by reducing the pressure to which the working fluid expands, below that of the atmosphere. The working fluid thereby gains more kinetic 10 energy than if it is simply expanded to the atmospheric pressure; but of this kinetic energy only a certain portion is abstracted by the turbine wheel or wheels, some kinetic energy still remaining in the fluid issuing 15 from the turbine wheels, which we reconvert into pressure energy as the working fluid is returning to the atmosphere.

The expansion nozzles of any elastic fluid turbine are preferably made of some material which is a poor conductor of heat and will stand high temperatures without the employment of a water jacket, and we prefer to use for the construction of such nozzles the material commonly known as soapstone, 25 which material may also be used for compression nozzles.

Some of the advantages of working with a vacuum in the internal combustion turbine by our invention may be mentioned as follows:—1st. With a given pressure in the combustion chamber the permissible temperature there is raised as has been explained above. 2nd. Owing to the increased speed of the working fluid at its entrance to the 30 turbine wheels and to the utilization of the speed possessed by the working fluid at its exit from the turbine wheels for returning it to the atmosphere, a given amount of kinetic energy may be abstracted from the working 35 fluid with a reduction in the number of turbine wheels or in their peripheral speed of rotation, or in both, below what is possible when the lowest pressure in the turbine 40 wheels is that of the atmosphere. 3rd. The 45 frictional resistance between the wheels and the fluid in the casing of the turbine is reduced by the reduction of the density of the fluid.

In our improved turbine we prefer to lower 50 the temperature of the working fluid after it has passed the turbine wheels. We prefer to do this by injecting water into it before it is returned to the atmosphere, the evaporation of a small quantity of water absorbing a 55 large amount of heat. By cooling the working fluid and thereby diminishing its volume at this point we diminish the amount of kinetic energy which must be left to it at its point of exit from the last turbine wheel, and 60 consequently increase the amount of the kinetic energy available for useful work. Let p_3 be the pressure of the working fluid at its exit from the turbine wheels and p_4 the pressure of the atmosphere; then the kinetic 65 energy which the fluid must possess when

leaving the turbine wheels depends upon the ratio $\frac{p_4}{p_3}$ and also upon its temperature at that point. We admit the cooling water in fine jets or spray so as to quickly evaporate and reduce the temperature of the working fluid in as short a passage as possible and without unnecessarily reducing its speed, and in such quantity as not to be in material excess of what is required for this purpose. 70

To avoid the heating and evaporation of the incoming water by conduction of heat from the casing of the turbine, we water jacket the channels, conveying the cooling water, up to as nearly as possible the point of 80 entrance of the cooling water to the working fluid.

After the working fluid has left the turbine wheels and has been cooled, it passes through a suitably constructed compression tube or nozzle in which its remaining kinetic energy is utilized for raising its pressure to that of the atmosphere. This compression tube may be made of a convergent-divergent section or of a divergent section only to suit the conditions of speed, density and pressure of the working fluid. 85

We consider the cooling of the working fluid before its compression to the atmospheric pressure will lead to increased efficiency but it may be found advisable to omit the cooling in some cases. When the cooling is omitted, then instead of using a separate compression tube, we may make the passages between the vanes of the last turbine wheel 100 of such a section as to provide for the raising of the pressure of the working fluid to the pressure of the atmosphere in this turbine wheel itself. The initial compression of the supply of air and the fuel if of a gaseous nature may be effected by a turbo-compressor or by any known system of compression pumps. 105

Where compression of air or gas by a turbo-compressor is desired as in the initial 110 phase of our series of operations above described, or for other purposes, a distinct advantage in reducing the number of turbine wheels required for such compression may be obtained by using a form of turbo-compressor which is the reverse of the motor turbine described above, that is, one in which the air or gas is first reduced in pressure through suitably shaped passages or nozzles, corresponding to phase F; thereby gaining 115 kinetic energy and then is given the necessary additional kinetic energy by the rotating wheels of the turbine, corresponding to phase D; and finally the total kinetic energy 120 is converted into pressure energy in suitably shaped nozzles, corresponding to phase C. 125

The attached drawing illustrates the nature of our invention.

The compressed air enters the combustion chamber *a* at *b* and the fuel is admitted at *c* 130

where it ignites and burns in the combustion chamber thus raising the temperature of the working fluid. The working fluid at a high pressure and high temperature then enters 5 the passage *d* and passes through the expansion nozzle *e* where it expands to below atmospheric pressure and gains kinetic energy and is reduced in temperature before reaching the vanes of the first turbine wheel 10 *f*. This nozzle *e* is so proportioned in a well understood manner that the expansion is carried below atmospheric pressure this being a special feature of this invention. After giving up a portion of its kinetic 15 energy to the wheel *f*, the working fluid passes through the guiding passages *g* to the second turbine wheel *h* which takes up a further portion of its kinetic energy. Further guiding passages and turbine wheels 20 may be added as required, but the working fluid after leaving the last turbine wheel, which in the diagram is marked *h*, has sufficient kinetic energy left to compress itself in the compression tube *j* to atmospheric 25 pressure. We may add the water spray for cooling as indicated at *k*, and provide to this the cooling jacket *l* as described, water being supplied to both at *m* and a sufficient 30 length of passage *n* to allow of the cooling of the working fluid by the water spray before compression to atmospheric pressure. As hereinbefore mentioned we may omit the water cooling and the special compression tube, and in that case we may construct the 35 passages between the vanes of the last turbine wheel of such a shape as to allow of the compression of the working fluid to atmospheric pressure in these passages themselves by means of kinetic energy left to the working 40 fluid for this purpose. The nozzles *e* and *j* may be made of soapstone. A casing *p* is provided to inclose the turbine parts.

Having now described our invention, what we claim and desire to secure by Letters Patent is:—

1. In an internal combustion turbine in combination means for forcing air and gas into the place of combustion where the mixture is burned to raise the temperature there- 50 in, means for reducing the pressure of the working fluid so formed to a pressure appreciably below that of the atmosphere so as to give kinetic energy to the working fluid, mechanical means for abstracting for useful

purposes a portion only of the said kinetic 55 energy, and finally means for raising the pressure of the working fluid to atmospheric pressure by its residual kinetic energy.

2. In an internal combustion turbine in combination means for forcing air and gas 60 into the place of combustion where the mixture is burned under constant pressure to raise the temperature therein, means for reducing the pressure of the working fluid so formed to a pressure appreciably below that of the at- 65mosphere so as to give kinetic energy to the working fluid; mechanical means for abstracting for useful purposes a portion only of the said kinetic energy, means for cooling the working fluid and thereby increasing its density, and finally means for raising the pressure of the working fluid to atmospheric pressure by its residual kinetic energy.

3. In an internal combustion turbine in combination, means for generating a working 75 fluid by internal combustion, means for reducing this working fluid to a pressure below that of the atmosphere, mechanical means for partially using its kinetic energy for useful effects and finally means for rais- 80 ing the pressure of the working fluid to atmospheric pressure by its residual kinetic energy.

4. In an internal combustion turbine in combination, means for generating a work- 85 ing fluid by internal combustion, means for reducing this working fluid to a pressure below that of the atmosphere, mechanical means for partially utilizing its kinetic energy for useful effects, a water spray passing 90 through a cooling jacket for cooling the working fluid so as to increase its density, and finally a compression tube for raising the pressure of the working fluid to atmospheric pressure by its residual kinetic energy. 95

In testimony whereof we have signed our names to this specification in the presence of two subscribing witnesses.
